(57) **CLAIM**

The ornamental design for a floor lamp with shelf, as shown and described.

DESCRIPTION

FIG. 1 is a front perspective view of a floor lamp with shelf, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the explosion state diagram of its front side thereof;

FIG. 10 is the explosion state diagram of its bottom side thereof;

FIG. 11 is a top view of its single layer thereof;

FIG. 12 is a bottom view of its single layer thereof;

FIG. 13 is a side view of its single layer thereof;

FIG. 14 is an enlarged detail view of area 14 in FIG. 1 thereof;

FIG. 15 is an enlarged detail view of area 15 in FIG. 2 thereof;

FIG. 16 is an enlarged detail view of area 16 in FIG. 2 thereof;

FIG. 17 is an enlarged detail view of area 17 in FIG. 9 thereof;

FIG. 18 is an enlarged detail view of area 18 in FIG. 10 thereof; and,

FIG. 19 is an enlarged detail view of area 19 in FIG. 12.

The broken lines in the drawings illustrate the portions of the floor lamp with shelf, which form no part of the claimed design.

The dash-dot-dash broken lines encircling the enlarged views are for annotative purposes only and form no part of the claim thereof.

1 Claim, 19 Drawing Sheets
